J. P. SCOTT, OF LEWISBURG, PENNSYLVANIA.

Letters Patent No. 70,904, dated November 12, 1867.

IMPROVED SCHOOL-DESK AND SEAT.

The Schedule referred to in these Letters Patent and making part of the same.

TO ALL WHOM IT MAY CONCERN:

Be it known that I, J. P. SCOTT, of Lewisburg, in the county of Union, and State of Pennsylvania, have invented a new and improved Combined School-Desk and Seat; and I do hereby declare that the following is a full, clear, and exact description thereof, which will enable those skilled in the art to make and use the same, reference being had to the accompanying drawings, forming part of this specification, in which—

Figure 1 is a front view of my improved combined school-desk and seat, showing the seat folded up against the desk.

Figure 2 is a vertical section taken in the line xz , fig. 1.

Figure 3 is a vertical section taken in the line yz , fig. 2.

Similar letters of reference indicate corresponding parts.

This invention relates to an improvement in the construction of a school-desk combined with a seat, and consists in such an arrangement and combination of parts that the seat and the desk may be separately adjusted in height to suit pupils of different sizes, and that the seat and a lid of the desk may be folded up when not in use, to be compact and out of the way when desired, as hereinafter more particularly described.

A A are supporting standards or legs on each end of the desk. B is the body of the desk, and C the seat. The upper ends of the standards A A are fitted in grooves or recesses in the ends of the body of the desk, to slide freely therin, in such manner that the desk may be raised or lowered to any required height, and secured by pins, a, or in any suitable manner. The seat C is hinged at both ends to the upper ends of slide-pieces b b, so that it may be folded up against the front side of the desk B or be let down to a level, when it is supported by segment arms or braces c c that are pivoted at one end to the slides b b, while the other ends are held in grooves or recesses in battens d d on the under side of the seat, in such manner that they close up or extend when the seat is folded or opened. The slide-pieces b b, to which the seat C is attached by hinges, are fitted in vertical grooves or recesses in the bases or supports A A to work freely therein in such manner that the seat may be raised or lowered to any desired height, and secured by pins e e, or by any other suitable device. A lid, f, is hinged to one side of the desk B in such manner that it can be folded over to lie on the top, or dropped down to lie close against the front part of the desk, as shown in fig. 2. For keeping the lid level, to serve for a writing-desk or table, when required, two folding brackets g g are placed at the ends of the desk. The body of the desk is hollow, forming a box or suitable receptacle for the slates and books of pupils, which may be set up on edge therein or on a shelf, h, which extends partly within the body of the desk. When the lid is let down it closes the hollow receptacle for books, etc., and protects them completely from dust, and also keeps them safe when the lid is locked.

It will be seen that the arrangement herein described presents great convenience for school purposes. The seat and the desk are both easily adjusted separately to any desired height to suit pupils of different sizes, and the seat and lid, or either of them, may be folded out of the way, making more room for sweeping, or for lectures or other purposes to which the room may be appropriated.

Having described my invention, I claim as new, and desire to secure by Letters Patent—

1. The arrangement of the school-desk B, supported on the sliding standards A A, and the seat C, hinged to the slide-pieces b b and supported by the segment arms c c, constructed, combined, and operating as and for the purposes herein described.

2. The lid f, hinged to the desk B, in combination with the folding brackets g g, in such manner as to fold on the top or close the hollow receptacle for books in the desk, arranged as herein set forth.

J. P. SCOTT.
